(57) **CLAIM**

The ornamental design for a camera for image detector, as shown and described.

DESCRIPTION

FIG. 1 is a top, front and left side perspective view of a camera for image detector showing my new design;
FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict environmental subject matter only and form no part of the claimed design.
